UNITED STATES PATENT OFFICE.

DONALD J. ANGUS, OF INDIANAPOLIS, INDIANA.

MOVABLE ELEMENT FOR METERS.

1,425,229.

Specification of Letters Patent. Patented Aug. 8, 1922.

Original application filed May 20, 1918, Serial No. 235,572. Divided and this application filed June 26, 1920. Serial No. 392,038.

To all whom it may concern:

Be it known that I, DONALD J. ANGUS, a citizen of the United States, residing at Indianapolis, in the county of Marion and State of Indiana, have invented a new and useful Movable Element for Meters, of which the following is a specification.

It is the object of my invention to provide an improved construction and mounting of the movable element of a meter, and of the marking device controlled thereby.

The general arrangement of the meter and the structure of the stationary element form the subject-matter of my co-pending application Ser. No. 235,573, the two-point suspension of the movable element on the torsion wire forms the subject-matter of my co-pending application Ser. No. 235,574, and the structure of the movable meter element and the details of its mounting on the torsion wire form the subject-matter of my co-pending application Ser. No. 235,572, all three of which applications were filed May 20, 1918.

The present application is a division of said application Ser. No. 235,572; and relates to the details of the pen and its mounting.

The accompanying drawings illustrate my invention as applied to an electric meter. Fig. 1 is a vertical section through an electric meter embodying my invention; Fig. 2 is a horizontal section, with some parts broken away, on the line 2-2 of Fig. 1; Fig. 3 is a vertical section on a larger scale, in partial elevation, through the working elements of the meter, with the central part broken away; Fig. 4 is a perspective on a larger scale of the mounting of the supporting staff of the movable element of the torsion wire; Fig. 5 is a longitudinal sectional detail of this staff and wire, with the parts broken away to allow the use of a still larger scale; Fig. 6 is a perspective view of the removable pen; and Fig. 7 is a perspective detail of the clip by which the pen is supported on the main supporting staff.

The main casing 10 of the meter is divided by a vertical partition 11 into a front compartment 12 containing the record-making parts and the rear compartment 13 containing the metering parts. The metering parts and the record-making parts are all supported on the partition 11. The rear compartment 13 is closed by a removable back 14; and the front compartment is

closed by a hinged front cover plate 15 which forms the front, sides, and top of such compartment and has windows 16 and 17 of glass or other transparent material in front and top.

Suitably mounted in the front compartment 12 are a supply roll 22 and a winding roll 23 of a record sheet 24; which passes over suitable guides 25 and 26 and a feed roller 27, so that it has a horizontal portion visible through the top window 17 and on which the record is made by a pen 28, and a vertical portion on which the most recently made part of the record is visible through the front window 16. The pen 28 carries a pointer 29 which moves over an indicating scale 30, so that visual indication of the instantaneous condition being measured is given. The record sheet is driven in any suitable manner, as by clockwork, preferably enclosed in a casing 31 mounted within the compartment 12. This driving means operates the winding roll 23 and the feed roller 27, in any suitable manner.

Mounted within the compartment 13 on the partition 11 is the stationary non-magnetic frame 35 of the metering parts of the meter. This frame in the electric meter shown carries in any suitable manner the stationary coils 36 which produce the desired magnetic field. At its upper end the frame 35 is provided with an ink well or cup, through an arc-shaped slot 38 in the cover 39 of which the rear end of the pen 28 dips to feed the pen by capillary action. Fasted to the lower end of the frame 35 there is a liquid-holding cup 40, into which a partition 41 from the frame 35 projects downwardly to form a baffle plate retarding the liquid movement therein. Suitably mounted in the lower end of this partition 41 is a disk 42 which in turn carries a split screw plug 43 for supporting the lower end of the torsion wire 44 on which the movable element of the meter is carried. The upper end of the torsion wire is correspondingly mounted in a disk 45 spring-pressed upwardly by a spring 46 within a hollow plug 47. This plug 47 has a screw-threaded mounting within one end of an adjusting lever 48 and in a pair of lock nuts 49, and the adjusting lever 48 rests on a bridge 50 mounted on the upper end of the frame 35. The upper face of the disk 45 and the lower end of the screw plug 43 are recessed to receive rivets in which the ends of the torsion

wire 44 are fastened. These rivets are preferably of the construction shown in my co-pending application Ser. No. 235,572. By a similar washer and rivet an intermediate 5 point of the wire 44 is fastened to but spaced from the wall of the main supporting staff 56 which carries the movable element of the meter; so that at its intermediate point the torsion wire and said staff are rigid with 10 each other, and when the staff turns about its axis, along which the torsion wire lies, the parts of the torsion wire above and below this riveted point are twisted or un-twisted. The details of this washer and 15 rivet are set forth in my aforesaid co-pending application.

The staff 56 is a flattened tube with a longitudinal slot extending its full length on the opposite wall from that on which the 20 intermediate rivet is fastened. Such staff is conveniently made from a strip of sheet metal bent in the desired shape. In order to hold the staff 56 in an upright position on the wall 34, it is provided, preferably at 25 the upper end, with an integral guide finger 57 which is bent down across the end of the staff and is provided with a hole 58 through which the torsion wire 44 extends. This provides a guiding support for the staff 56 30 on the wire 44 at a point removed from the point of rigid attachment formed by the intermediate rivet 51. The general idea of mounting the movable element of the meter on the torsion wire by this two-point support—one point of rigid attachment and one guiding point—forms the subject-matter of 35 my co-pending application Ser. No. 235,574. Mounted on the staff 56, in a manner immaterial to the present application but preferably in the manner set forth in my co-pending application Ser. No. 235,572, are the 40 movable coils 61 of the meter. In the meter shown there are two pairs of said movable coils, each pair acting as a unit and co-operating with one pair of the stationary coils 36, of which there are also two pairs shown; but the number of sets of co-operating coils 45 may be anything desired. All the sets act correspondingly to produce a deflection of 50 the movable element of the meter.

A sheet metal clip 75 (shown in detail in Fig. 7) is mounted on the upper end of the main supporting staff 56, for carrying the pen 28. This sheet metal clip 75 has two upwardly extending arms 76 in which there 55 are registering slots 77, the plane determined by these slots 77 being displaced forwardly from the torsion wire 44, as is clear from Fig. 3. The slots 77 receive a knife blade 78 on which is mounted a pen carrier 79. This pen carrier has attached to it at its forward end the pen 28, by a pair of fingers 80 surrounding the tubular body of the pen (as is clear from Fig. 6). To the rear of the knife 60 blade 78, the pen carrier 79 has a curved off-

set portion 81 where it passes the torsion wire 44, so that it will not interfere with such torsion wire; and beyond such offset portion is provided with a rearwardly projecting screw 82 on which is screw-mounted 70 a counterweight 83, which may be adjusted to control the vertical position of the marking end of the pen 28 and its downward pressure on the record sheet. The pen unit, comprising the pen 28 proper, the pen carrier 79, and its supporting knife blade 78, may readily be removed by lifting the knife blade 78 from the slots 77. Such removal is desirable for convenience and protection in shipping and installing the meter, and in 80 filling and cleaning the pen.

In order to adjust the torsion of the torsion wire 44 to bring the pen 28 and the pointer 29 to the proper zero point, the adjusting lever 48 may be operated to vary the 85 circumferential position of the upper end of the torsion wire 44. This is conveniently done by providing the outer end of the adjusting lever with a fork 85, through which an adjusting screw 86 projects. This adjusting screw is provided with a slotted nut 87 which co-operates with the fork 85, so that when the screw 86 is turned the nut 87 and therefore the outer end of the adjusting lever 48 are moved to vary the circumferential position of the upper end of the torsion wire 44. Preferably the screw 86 extends through the partition 11, and is provided in the front compartment 12 with a knurled head 88, whereby it may be operated, the screw being held in proper position with relation to the partition 11 by the head 88 and a pair of lock nuts 89 in the compartment 13.

What I claim is:—

1. In a meter, a torsion wire, a movable meter element mounted on said wire, a record sheet, and a marking device mounted on and freely removable from said movable meter element and co-operating with said record sheet.

2. In a meter, a torsion wire, a movable meter element mounted on said wire, a pair of knife blade supports carried by said movable meter element, a knife blade removably resting on said knife blade supports, a marking device mounted on said knife blade, and a record sheet co-operating with said marking device.

3. In a meter, a movable meter element, an ink well, a pen support removably mounted on said movable meter element, a pen carried by said pen support and having a feeding end dipping into said ink well for capillary feed therefrom, and a record sheet 120 with which the marking end of said pen co-operates, said pen and pen support being freely removable as a unit from said movable meter element and said ink well.

4. In a meter, a movable meter element, a 130

pair of knife blade supports carried by said movable meter element, a knife blade removably resting on said knife blade supports, a marking device mounted on said knife blade, an ink well, and a record sheet, said pen having a feeding end dipping into said ink well for capillary feed therefrom and a marking end co-operating with said record sheet, and said pen and knife blade being freely removable as a unit from said ink well and said knife blade supports.

5. In a meter, the combination of a movable element mounted for movement about an axis, a record sheet, and a pen pivotally mounted on said movable element on an axis transverse to the axis of said movable element and freely removable therefrom and cooperating with said record sheet.

6. In a meter, the combination of a movable element mounted for movement about an axis, said movable element being provided with a pair of knife blade supports transverse to its axis, a knife blade removably resting on said knife blade supports, a pen carried by said knife blade, and a record sheet co-operating with said pen.

7. In a meter, the combination of a movable element mounted for movement about an axis, a record sheet, a pen pivotally mounted on said movable element on an axis transverse to the axis of said movable element and freely removable therefrom and co-operating with said record sheet, and an adjustable counter-balance on said pen to permit adjustment of the force with which it engages the record sheet.

8. In a meter, the combination of a movable element mounted for movement about an axis, said movable element being provided with a pair of knife blade supports trans-

verse to its axis, a knife blade removably resting on said knife blade supports, a pen carried by said knife blade, a record sheet co-operating with said pen, and an adjustable counter-balance on said pen to permit 45 adjustment of the force with which it engages the record sheet.

9. In a meter, a torsion wire supported at both ends, a movable meter element mounted on said wire, a record sheet, and a marking device mounted on and freely removable from said movable meter element and co-operating with said record sheet.

10. In a meter, a torsion wire supported at both ends, a movable meter element 55 mounted on said wire, a record sheet, and a marking device co-operating with said record sheet and controlled by said movable meter element.

11. In a meter, a movable meter element 60 movable on a substantially vertical axis; a record sheet; a stationary ink well; and a pen mounted on and freely removable from said movable meter element, co-operating with said record sheet, and supplied from 65 said ink well.

12. In a meter, a movable meter element; a record sheet; an ink well; a pair of knife blade supports carried by said movable meter element; a knife blade removably resting on 70 said knife blade supports; and a pen mounted on said knife blade, co-operating with said record sheet, and supplied from said ink well.

In witness whereof, I have hereunto set 75 my hand at Indianapolis, Indiana, this twenty-fourth day of June, A. D. one thousand nine hundred and twenty.

DONALD J. ANGUS.
